UNITED STATES PATENT OFFICE

GEORGE D. OVERHOLTZ, OF LEETSDALE, PENNSYLVANIA, ASSIGNOR TO RITER-CONLEY MANUFACTURING COMPANY, OF PITTSBURGH, PENNSYLVANIA, A CORPORATION OF PENNSYLVANIA

OUTDOOR ADVERTISING STRUCTURE

Application filed July 3, 1929. Serial No. 375,814.

This invention relates to improvements in outdoor advertising structures, and more particularly to improvements in the molding supporting means for such structures.

5 These structures are of steel construction and include a framing embodying a series of A-frames formed of angle members or other structural shapes and a plurality of horizontally extending structural members secured to the vertically extending members of the A-frames. The poster-receiving panel, comprising several sections, and the means for supporting the molding of the panel including top, bottom and sides, are mounted 10 on and secured to the steel framing. The molding is usually formed of sheet metal properly shaped to provide an attractive appearance. In some instances, however, a wooden molding is employed.

20 As heretofore constructed, the means for supporting the molding have been the source of considerable trouble in erecting and dismantling and in providing efficient means for maintaining the molding in the desired 25 position relatively to the poster-receiving panel portion of the outdoor advertising structure.

The prime object of the present invention is to provide simple, strong and efficient 30 means for supporting the molding or moldings employed in structures of the character stated.

Another object of the present invention is to provide a molding supporting means that 35 may be readily assembled on and disassembled from the structural framing.

In the accompanying drawings, which illustrate applications of my invention:

40 Fig. 1 is a front elevational view of an outdoor advertising structure embodying my invention;

Fig. 2, an end view;

Fig. 3, an enlarged sectional view taken on line III—III of Fig. 1;

45 Fig. 4, an enlarged horizontal sectional view taken on line IV—IV of Fig. 1;

Fig. 5, a perspective view of a Z-bracket employed;

50 Fig. 6, a similar view of another form of bracket embodied in my invention; and

Fig. 7, a detail sectional view showing a construction including a molding made of wood.

Referring to the drawings, the steel framing comprises a series of A-frames generally 55 designated 5, and 6 a plurality of horizontally extending members secured to the uprights or vertically extending members 7 of the A-frames. This framing is designed to support the poster-receiving panel made up 60 of a series of steel panel frames and sheet metal coverings, said sections being designated 8.

The molding surrounding the poster panel 65 extends along the top, bottom and the two sides, and, as illustrated and as preferred, comprises a sheet metal construction shaped and bent to produce an attractive design. As shown, A designates the top molding, B the bottom, and C the side moldings, all having 70 substantially the same configuration and made from the same material. The moldings are adapted to be positioned upon supporting means which are in turn supported by the steel framing. 75

The supporting means constitute an important and characteristic feature of my invention. Said means, for the top molding A and the bottom B, are substantially similar and include an irregularly shaped channel-like member or plate bracket structure 9, having a straight flat element 10 formed with bolt-receiving openings 11, and a bent member 12 formed with a portion 13 spaced from and extending parallel with element 10 and 80 with bent portions 14 and 15. The spaced-apart elements or members 10 and 12 are joined by a vertically extending wall 16.

As clearly shown by the drawings, these 85 plate brackets 9 are shaped to receive correspondingly shaped portions a, b and c of the moldings A, B and C, the top molding being secured to the brackets by headed bolts 17 and the bottom molding B by bolts 18. In addition to the portions a, b and c, each top 90 and bottom molding includes an irregular curved portion d and a flange or bent portion e.

The molding carrying brackets 9 are designed to be supported from the vertically ex- 100

tending members or uprights 7 of the steel framing, and for this purpose I employ Z-shaped plate brackets 19 having the vertically extending portions 20 and 21 thereof respectively formed with bolt openings 22 and 23.

Attaching bolts 24, extending through the uprights 7 and the portions 20 of the Z-plates and the portions 15 of the brackets 9, are employed and, in addition thereto, headed studs or pins 25 for securing the portions 21 of the Z-plates are used.

In conjunction with the Z-plates and the brackets 9, I employ angle members or brackets 26 having the vertically extending member 27 of the respective brackets positioned between the part 20 of the Z-plate and the part 15 of a bracket 9. The short members 28 of brackets 26 are arranged in contact with the elements 10 of the brackets, and are each formed with an opening registering with the opening 11. 17 and 29 designate headed studs passed through the said openings, and serving to tie the said parts together.

In connection with the upper molding supporting means, I preferably employ a reinforcing channel member 30 which extends across the poster panel and is employed for supporting means therefrom during the operation of pasting posters on the panel portion of the outdoor advertising structure.

The supporting means for the side moldings C are particularly shown by Fig. 4. In this form, the supporting means are attached to the horizontally extending members 6 of the framing instead of to the uprights 7, and the Z-plates or brackets 19 are omitted. In place of the said plates 19, I employ spacer members 31. Members 31, as illustrated, are small channel sections interposed between the horizontal members 6 and the members 26 of the molding supporting means. Otherwise the supporting means for the side moldings C are similar to the supporting means for the molding B. Bolts 32 are provided for attaching the molding supporting means to the members 6.

As particularly shown in Fig. 1 of the drawings, I have shown at each corner of the panel structure the molding formed with telescoping corner portions D, comprising short sections of the metal molding mitered and welded together.

In the form of Fig. 7, I have particularly shown a desirable construction in cases where wooden moldings W are employed. In this instance, the Z-brackets 19 are employed and arranged as shown in the other forms.

I claim:

1. In an outdoor advertising structure, the combination with a support framing, of molding supporting means associated with the framing and including a hollow angular bracket over which the molding is positioned,

a second bracket member, means for joining the two bracket members, and means for attaching said brackets to a member of the support framing.

2. In an outdoor advertising structure, the combination with a support framing, of molding supporting means associated with the framing and including a hollow angular bracket over which the molding is positioned, a second bracket member, means for joining the two bracket members, and means for attaching said brackets to a member of the support framing, said attaching means including a Z-shaped member.

3. In an outdoor advertising structure, the combination with a member of a support framing, a molding supporting means associated with the framing including a hollow angular bracket member over which sheet metal molding is positioned, a second bracket member engaging the hollow bracket member, spacing means between the support member and said brackets, and means for attaching the brackets to the support member.

4. In an outdoor advertising structure, the combination with a support framing and a sheet metal molding, of sheet metal molding supporting means associated with the framing and including a hollow angular bracket over which the molding is positioned, a second bracket member, means for joining the two bracket members and the sheet metal molding, and means for attaching said brackets to a member of the support framing.

In testimony whereof I affix my signature.

GEORGE D. OVERHOLTZ.
